LIFEBOAT ENGAGING AND RELEASE GEAR.

Robert Cameron Fawkes, Ilford, England

Application December 27, 1951, Serial No. 263,654

Claims priority, application Great Britain July 3, 1951

6. Claims. (Cl. 9—45)

Lifeboats and such like auxiliary boats or vessels, hereinafter referred to generally as lifeboats, are generally held on shipboard by being slung each between a pair of davits which have suitable tackles such as cable or chain with hooks at the ends which engage with coupling elements at the fore and aft ends respectively of the boat.

The object of this invention is to provide an improved form of tackle engaging and release unit for installation one at each end of a lifeboat to enable the latter to be suspended between spaced-apart supporting tackles, the unit providing for fitting the tackle engaging elements at variable centres, as between the fore and aft ends of the boat and to provide for quick release from the tackles when the boat is waterborne.

In order that the invention may be readily understood reference will now be made to the accompanying drawings which illustrate a tackle engaging and release unit according to the invention and a lifeboat incorporating a pair of said units and operating gear therefor.

In the drawings:

Figure 1 is a diagrammatic view in longitudinal elevation of a lifeboat fitted with the said units and gear,

Figure 2 is a diagrammatic view in plan of the lifeboat showing particularly the layout of the operating gear,

Figure 3 is a cross section, generally on the line III—III in Figure 4, of one of the unit assemblies mounted at the fore or aft end of the boat as may be,

Figure 4 is an elevation of the housing or support for the retractable tackle engaging pin and its pendulum loading lever, and

Figure 5 is a detail in side elevation of the spacer members between the pair of mounting frame members of the assembly shown in Fig. 3.

The gear shown comprises two identical unit assemblies A and B (Figures 1, 2 or 3) one of which is shown in detail in Figure 3. Each unit assembly comprises a pair of elongated frame bar members 1, 1, mounted in parallel array at the fore or aft end of the boat as the case may be, the frame members defining spaced apart cheeks which enable the hook or ring of the supporting tackle to be passed therebetween with adequate clearance. Along the length of each frame bar member 1 are two series of holes 2 and 3 to provide for selectively positioning the tackle engaging elements (4) of the units at the appropriate centres to suit the boat; such a feature has the advantage of flexibility in mounting especially when the centres between the supporting tackle hooks are not known when the boat is ordered. Each tackle engaging element comprises a sliding pin 4 which engages in opposite holes of a pair of the series of holes 3 to form a bridge across the cheeks of the pair of opposite frame bar members 1, with which bridge the tackle can be engaged. The pin 4 is supported in a boss 5 on a housing bracket plate 6 of triangular shape (see Figure 2). At the two base corners of the plate 6 two bolt holes 7 are provided so spread as to align with holes in the series 2 when the pin 4 is engaging in a pair

2

in the series 3, and this permits fixing bolts 8 to be passed through the aligned holes for clamping the plate to the frame bar members 1. A spacer 9 is interposed between the frame members 1, being of U-shape to come under the pin 4 and having lugs 10 at each side of the base to receive the fixing bolts 8. The spacer extends up and around the pin with plenty of clearance to allow for the insertion of the supporting tackle hook, and provides a general protection for the various parts, being terminated at the mouth by flanges 11 which lie over the edges of the frame members 1 to provide a lead-in for the tackle and a protection for the frame edges.

The pin 4 is held normally in the closed or bridging position by a pendulum loading lever 12 which is carried by a pivot 13 in turn supported by a pair of parallel lugs 14 projecting at right angles from the mounting plate 6 and from under the pin housing boss 5. It is convenient that the plate 6, boss 5 and lugs 14 are made as a one piece casting. The short arm of the lever extends above the pivot 13, terminating in a knob 15 which rotatably fits in an axial slot 16 in a tail piece 17 of the pin 4. The long arm of the pendulum has a bob-weight 18 secured thereto, adjustably if desired, and terminates in an eye piece 19 for connection thereto of the operating cable. It will be observed that the pendulum lever 12 will tend to keep the pin 4 in the closed position shown in Figure 3, but that when the lever is turned clockwise, the pin is retracted until that portion which bridges the frame members 1 is withdrawn into the housing 5. Such a retraction of the pin 4 can readily be effected when the boat is waterborne after lowering by the tackles which support it along the ship's side.

The operating mechanism for the retractable pins 4 at each end of the boat, provides for simultaneous retraction thereof, by means of flexible transmission elements in the form of chains or cables 20 moving over pulleys 21 which are connected at one end to the eye pieces of the respective pendulum lever 12 and at the other end to wire rods 22 supported in guides 23. An operating handle 24 connects the flexible elements from either end at an intermediate point, and is readily available so that a pull thereon draws the bob-weights 18 inwards towards the boat centre line so that the pendulum levers 12 turn clockwise to withdraw the pins 4. When the handle is released, the weights 18 return the levers 12 and therefore the pins 4 to the normal closed position. The operating gear is carried under the side seating immediately behind the buoyancy tank cleading as provided in the usual lifeboat, so that the gear forms no obstruction.

Various alternatives are possible to the method of quick release herein shown. Thus, a simple hook with selecting adjustment as to position may be employed to provide for easy release or vice versa when the boat is waterborne.

I claim:

1. Tackle engaging and release unit for installation on a lifeboat, comprising a mounting frame for fixing lengthwise fore and aft at one end of the boat including spaced apart vertical cheeks, means clamping said cheeks together, including a U-spacer having a mouth which forms a tackle lead-in, a tubular housing boss projecting from one cheek in coincidence with co-axial holes in said cheeks which are disposed between the bight and the mouth of the U-spacer, a horizontal tackle engaging element slidably mounted in said housing boss from a tackle engaged position in which said element engages said holes so as to bridge said cheeks, to a tackle release position clear of the space between said cheeks and vice versa, a lateral projection from under said housing boss, a pendulum loading lever carried by a pivot at the end of said projection, said lever having

one arm connected to said element and a weighted arm which depends below the pivot to bias the lever normally to a position in which it holds the element in said bridging position.

2. Tackle engaging and release unit according to claim 1, wherein said projection from under the housing boss comprises a pair of lugs forming a fork and said pivot is carried between the ends of the fork with the lever arms located between the lugs, and an abutment on said fork inwardly of the pivot to engage the first of said arms of the loading lever whereby to determine the bridging position.

3. Tackle engaging and release unit for installation in a lifeboat, comprising a mounting frame for fixing lengthwise fore and aft at one end of the boat including spaced apart cheeks, a housing, means clamping said cheeks together and the housing to one of said cheeks so that it projects laterally therefrom, said means including a U-shape spacer between the cheeks, a tackle engaging element embraced by said spacer and slidably mounted in said housing from a tackle engaged position bridging said cheeks to a tackle release position clear of the space between said cheeks and vice versa, and a pendulum loading lever pivotally mounted on said housing, and connected to bias the said element to the bridging position.

4. Tackle engaging and release unit for installation on a lifeboat comprising an elongated mounting frame for fixing lengthwise fore and aft at one end of the boat, said frame consisting of an assembly of two parallel bars defining spaced apart cheeks, a plurality of securing positions defined by groups of holes in two rows of holes between the ends of said bars, a slideable tackle engaging element bridging said cheeks, a housing for said element projecting laterally from one of said cheeks, pendulum loading means pivotally carried on the housing, a connection between the element and the loading means to hold the element in the bridging position, and means including a U-shape spacer securing both the

bars together and the housing to one of the bars in one of said positions with the tackle engaging element bridging coincident holes in said bars and the spacer embracing said element.

5. Tackle engaging and release unit according to claim 4 and including flanges to said spacer overlying the longitudinal edges of said bars to provide a lead-in guide and a protector during engagement or release of the tackle.

10 6. Tackle engaging and release unit for installation in a lifeboat, comprising a mounting frame including spaced apart vertical cheeks for fixing lengthwise fore and aft at one end of the boat, a housing bracket, including a tubular boss projecting laterally therefrom, a tackle engaging element slideable in said boss, said cheeks having a group of holes defining a securing position for said bracket on the side of one of said cheeks and a housing for the said element in bridging position across the cheeks, means clamping said cheeks together and the bracket to said cheek including bolts passing through some of said holes and a U-shape spacer disposed between said cheeks and embracing said element in bridging position, and a pendulum loading lever pivotally mounted on said bracket and having an upward arm connected to said element and a downward arm provided with a weight which holds the lever with said element in bridging position.
